UNITED STATES PATENT OFFICE

2,175,640

AIR-METHOD ELECTRIC CLEANER AND
CARPET SWEEPER

Daniel Benson Repleglo, Berkeley, Calif., assignor
to The Ohio Citizens Trust Company, Toledo,
Ohio, a corporation of Ohio, as trustee.

Original application March 26, 1935, Serial No.
13,164. Divided and this application December
19, 1935, Serial No. 55,290

7 Claims. (Cl. 15—8)

The invention relates to a cleaning apparatus and more particularly to a portable electrically operated cleaner utilizing the cleaning effect of swiftly moving air in combination with the cleaning action of a positively driven surface engaging member, preferably a revolving brush. Thus the apparatus combines the functions of an air-method cleaner and a carpet sweeper.

The present application is a division of Patent 10 2,085,042, issued June 29, 1937.

In designing the apparatus it is my aim to a large extent to utilize standard and interchangeable parts, connections and the like, which are covered by my prior patents and which are included in what is known as the "Air-Way" system, the term "Air-Way" being covered by registered trade-mark.

The principal object of the invention is to provide a cleaner carrying an electrically actuated high speed centrifugal fan for producing suction in a floor tool or nozzle, an independent motor for operating a floor engaging member or brush within the nozzle, and an improved driving mechanism interposed between the brush and motor, the parts being compactly and conveniently arranged.

Other objects of the invention will appear hereinafter by reference to the accompanying drawing and the following detailed description, in which various specific embodiments of the inventive thought are set forth by way of illustration, rather than by way of limitation.

In the drawing:

Figs. 1, 2 and 3 are respectively, top, side and bottom views of one form of the combined sweeper and cleaner embodying my invention and including a wire frame for supporting the dust collector bag;

Fig. 4 is a perspective detail view of a removable dust cap or valve with which the cleaner is equipped when employed for floor cleaning purposes;

Fig. 5 is a perspective view of an auxiliary cleaning attachment or hose which may be substituted for the dust cap; and

Fig. 6 is a perspective view of a hollow extension device or handle which may be used as part of the auxiliary cleaning equipment.

According to my invention, I provide in connection with a suction cleaner, a floor tool including a suction chamber, a rotary agitator therein, a throat extending upwardly and rearwardly therefrom, a fan case at the upper end of the throat, a fan motor extending downwardly and rearwardly from the fan case, and an agita-

tor driving motor occupying the space between the fan motor and the suction chamber, said suction chamber and motors being compactly arranged.

Referring particularly to the drawing, reference numeral 18 denotes an electric motor employed for driving a high-speed centrifugal suction producing fan mounted within fan casing 11, the exhaust outlet of which is indicated at 12. An inlet to the fan is covered by a removable transparent cap or valve 13 having an opening 14 communicating with the fan and a side opening 15 communicating with the conduit 16 or throat leading to the suction chamber of the floor tool or nozzle 17, which tool may be made removable if desired.

The fan motor 18 may be supplied with current through an inlet 18 by means of a suitable conductor cord, not shown, and the motor casing is also shown as provided with an outlet plug 19 from which current may be supplied through a detachable connector 20 to a separate motor 21 driving a brush or other positive surface engaging member 22, within the nozzle 17, through suitable driving means 23, herein shown as a belt which passes through the rear wall of the nozzle. It will be noted that the motor 21 is compactly arranged beneath the upwardly and rearwardly extending throat 16, and between the nozzle 17 and fan motor 18. As shown, chambered arms or castings 24, 24 extend rearwardly from the main casting, one of said arms receiving the belt wheel 25 on one end of the motor shaft. Ordinarily but one belt will be necessary, but the second projection 24 is preferably made identical with the one which receives the belt wheel, thus lending balance to the structure. The brush motor 21 may, if desired, be removable supported between the two projecting arms or castings. This motor may be removed, if desired, for the purpose of repair, cleaning, etc.

It should be noted that in the arrangement herein set forth the motor 21 will be fully protected from shock or blow, being supported above the floor by the bracket arms 24, 24 and being protected in front and rear by the floor tool nozzle 17 and fan motor 18, and being protected above by the throat 16, all of which elements are of very substantial construction. By means of this protection the bracket arms 24, 24 are sufficient support for the motor 21 which thus is readily accessible for cleaning, oiling or repair. The entire arrangement is convenient, compact and economical. It is also to be noted that the inventor contemplates that the nozzle or floor

tool 17 together with the throat portion 18 may be removable from the body of the cleaner including the fan casing, as illustrated, for example, in my Patent No. 1,912,386 dated June 5, 1933, and in my Patent 2,120,260, dated June 14, 1938.

As shown, the apparatus is resiliently supported by two pairs of rollers, one pair 26, 26 being carried by the castings 24, 24 and the other 10 pair 27, 27 by the casing of the fan motor 18.

Where it is desired to employ the apparatus for purposes other than cleaning floors the cap 13 may be removed and an auxiliary connector 58 inserted in place thereof. This connector, as 15 shown, is formed at one end of a flexible hose 51, the opposite end of which 52 may serve as a nozzle, or if desired, a further extension member 53 may be connected at the reduced end 54 of the nozzle through an attaching member 56. 20 Any number of extension devices may be secured together in this manner so as to reach the desired location, as for example, the walls or ceiling of a room or the furniture or other contents of the room. The extension members may be similar to those disclosed in my prior Patent No. 1,533,271, dated April 14, 1925.

Dust laden air from the floor tool or from the auxiliary cleaning attachment may be directed through the discharge outlet 12 through suitable 30 connections, herein shown as including a swiveled L member 28 and a detachable thimble or deflector 29, extending into a reduced inlet mouth 38 of a suitable dust collector 31. The dust collector is preferably composed of porous paper 35 and may be suitably reinforced, if desired, in a manner disclosed in my prior patents and applications, see for example my Patent No. 1,416,876, dated May 23, 1922, and my Patent 2,123,913, dated July 19, 1938. The reinforcement, where employed, may take the form of an outer removable cover or may be integral with the bag. The connections between the bag mouth and the bag discharge outlet 12 may be of any suitable type, such as disclosed for example in 45 my prior patents and applications, see for instance my Patent No. 2,009,455, dated July 30, 1935, and my Patent 2,123,912, dated July 19, 1938.

As shown, the bag 31 is supported within a wire 50 framework designated generally by the reference letter A, which serves as a handle for the portable cleaner. The frame is light in weight, inexpensive in construction, and serves to support the bag when inflated in such a manner as to 55 prevent strain thereon, particularly during the operation of raising and lowering the handle.

The frame A may be composed of a plurality of rods constructed of umbrella steel or other suitable material. As shown, the frame includes an 60 upper pair of rods 32 having eye portions 33, 33 at one end thereof removably and hingedly connected to bracket members 34, 34 mounted on conduit members 12 and 28 respectively. It will be noted that the axis of rotation of the swiveled 65 member 28 is substantially in alignment with the ends of the brackets 34, 34. The rods 32, 32 being resilient and springy can easily be applied to the brackets, and when so applied there is no danger of accidental removal, but when desired they can 70 be easily taken off, thus separating the entire handle portion from the body of the cleaner by spreading the eyes laterally to clear the pivots.

At the rear the rods 32, 32 are retained by a 75 collar 35 into the opposite end of which fits a grip or handle 36. Also extending from the collar 35

in a forward direction are a pair of lower frame members or wires 37, 37, which are supported at their opposite ends by a front frame 38 which connects with the upper frame and is likewise preferably composed of resilient wires. This front frame is so constructed as to support the front of the bag in such a manner as to relieve strain, particularly when the bag is inflated. The numeral 38 designates an extension member, herein shown as attached to the front frame, which serves as an abutment and provides a stop so that by pressing down on the handle the abutment 38 will be caused to engage the motor casing and on further application of pressure the floor tool may be tilted upwardly about the rear rollers 27 as a fulcrum.

It will be obvious that when the bag is inflated as it will be when dust laden air is entering the same from the dust discharge outlet, the bag will be supported within the frame in such a manner as to avoid all strains. The frame may accordingly replace other reinforcement of the bag if desired, permitting the use of a plain porous bag.

The rear end of the bag is shown as provided with a clip 40 to which is attached a suitable 2 flexible connector 41, the other end of which is attached to a hook 42 which may extend from the grip portion 36. The length of the connector 41 may be adjusted as desired, or this member may be in the form of a spring so that the bag will 3 be held under constant tension of any desired degree. Obviously by screwing the hook 42 inwardly or outwardly, the degree of tension may be varied as desired.

The bag supporting means herein described is 3 claimed in my Patent 2,085,042.

I claim:

1. A portable electric suction cleaner and 40 sweeper comprising a floor tool provided with a suction nozzle chamber, a rotary agitator disposed within the suction chamber, a throat extending upwardly and rearwardly therefrom, a fan casing at the upper end of the throat provided with a fan motor extending downwardly and rearwardly of the said fan casing and a separate 45 agitator driving motor disposed within the space between the fan motor and the suction chamber.

2. A portable electric suction cleaner as set forth in claim 1, including a chamber extending 50 from said suction nozzle chamber to said driving motor, and driving means extending from said motor to said agitator through said chamber.

3. In a portable electric suction cleaner and carpet sweeper, a floor tool casing, a throat 55 extending upwardly and rearwardly therefrom, a fan casing at the end of the throat remote from the floor tool casing, and a fan motor casing extending downwardly and rearwardly from the fan casing, said floor tool casing, throat, fan 60 casing and motor casing providing a protected space beneath the throat and between the floor tool casing and motor casing, a rotary agitator housed within the floor tool casing, and an agitator motor for driving the rotary agitator wholly 65 mounted within said protected space.

4. In a portable electric suction cleaner and carpet sweeper, a floor tool casing, a throat extending upwardly and rearwardly therefrom, a fan casing at the end of the throat remote from 70 the floor tool casing, and a fan motor casing extending downwardly and rearwardly from the fan casing, said floor tool casing, throat, fan casing and motor casing being rigidly connected, and providing a protected space beneath the throat 75

and between the floor tool casing and motor casing, a rotary agitator housed within the floor tool casing, and an agitator motor for driving the rotary agitator wholly mounted within said protected space.

5. A portable electric suction cleaner and sweeper, comprising a floor tool suction nozzle, a rotatable agitator mounted within the nozzle, a motor actuated suction producing fan mounted adjacent to but at the rear of the suction nozzle and spaced therefrom and having its motor extending downwardly from the fan casing, a throat connecting the nozzle and the fan casing, an independent motor occupying the space beneath said throat intermediate said nozzle and said fan motor, a pair of bracket arms extending rearwardly from the nozzle and supporting the ends of the motor shaft, and a driving belt for said agitator actuated by said independent motor.

10. 6. A portable electric suction cleaner and sweeper, comprising a floor tool suction nozzle, a rotary agitator therein, a throat extending upwardly and rearwardly from the nozzle, a fan case at the upper end of said throat, a fan motor extending downwardly and rearwardly from the fan case, bracket arms extending rearwardly from the suction nozzle one on each side of the throat, a

15. 7. A portable electric suction cleaner and sweeper, comprising a floor tool suction nozzle, a rotary agitator therein, a throat extending upwardly and rearwardly from the nozzle, a fan case at the upper end of said throat, a fan motor extending downwardly and rearwardly from the fan case, bracket arms extending rearwardly from the suction nozzle one on each side of the throat, an agitator driving motor occupying the space between the fan motor and the nozzle, and having the ends of its shaft mounted within the bracket arms, and a driving belt for said agitator actuated by said last named motor and extending through the rear wall of said nozzle, at least one of said bracket arms being chambered and housing the portion of said driving belt which is outside the nozzle.

20. 25. DANIEL BENSON REPLOGLE. 25
